(57) **CLAIM**

The ornamental design for a bathroom play station, as shown and described.

DESCRIPTION

FIG. 1 is a right front perspective view of a bathroom play station showing our new design.

FIG. 2 is a left front perspective view of the embodiment of FIG. 1.

FIG. 3 is a front elevational view of the embodiment of FIG. 1.

FIG. 4 is a rear elevational view of the embodiment of FIG. 1.

FIG. 5 is a left side elevational view of the embodiment of FIG. 1.

FIG. 6 is a right side elevational view of the embodiment of FIG. 1.

FIG. 7 is a top plan view of the embodiment of FIG. 1; and, FIG. 8 is a bottom plan view of the embodiment of FIG. 1.

The broken lines represent portions of the design that form no part of the claim.
